(57) **CLAIM**

The ornamental design for an animal toy, as shown and described.

DESCRIPTION

FIG. 1 is a top, front, right perspective view of an animal toy showing our new design.

FIG. 2 is a bottom, front, right perspective view of the animal toy.

FIG. 3 is a top plan view of the animal toy.

FIG. 4 bottom plan view of the animal toy.

FIG. 5 front elevation view of the animal toy.

FIG. 6 rear elevation view of the animal toy.

FIG. 7 is a right side elevation view of the animal toy; and, FIG. 8 is a left side elevation view of the animal toy.

The broken lines shown in the drawings depict portions of the animal toy that form no part of the claimed design.

1 Claim, 6 Drawing Sheets
